(57) **CLAIM**

The ornamental design for a spring probe contact assembly as shown and described.

DESCRIPTION

FIG. 1 is a Top Front Right Side Perspective view;
 FIG. 2 is a Bottom Rear Left Side Perspective view;
 FIG. 3 is a Front view;
 FIG. 4 is a Rear view;
 FIG. 5 is a Left view;
 FIG. 6 is a Right view;
 FIG. 7 is a Top view; and,
 FIG. 8 is a Bottom view.

1 Claim, 5 Drawing Sheets---
